United States Patent Office.

JOSEPH ADAMS, OF CLEVELAND, OHIO.

Letters Patent No. 80,797, dated August 11, 1868.

IMPROVEMENT IN WASH-BOILERS.

The Schedule referred to in these Letters Patent and making part of the same.

TO ALL WHOM IT MAY CONCERN:

Be it known that I, JOSEPH ADAMS, of Cleveland, in the county of Cuyahoga, and State of Ohio, have invented certain new and useful Improvements in Wash-Boilers; and I do hereby declare that the following is a full and complete description of the same, reference being had to the accompanying drawings, making part of this specification, in which—

Figure 1 is a top view of the boiler.

Figure 2 is a longitudinal section in the direction of the lines $z-z$ in fig. 1.

Figure 3 is a view of the base detached from the boiler.

Like letters of reference refer to like parts in the different views.

My improvement consists in the construction of a base, with a cover of cloth or wire gauze, and frame, applied to a wash-boiler for the purpose of cleaning clothes. A description of the same is as follows:

A represents the boiler; B, the base, which is constructed of wood or other suitable material, and is shaped to conform to the boiler, having the two circular cavities or openings C. Around the edge of these cavities are the pins D, projecting towards the centre, as shown.

In the middle of the frame is the elongated opening E, over which the wire frame F is arranged, as seen in the drawing, extending to the top of the boiler, and having the ends firmly fixed in the base, B.

An apron, G, of cloth or wire gauze, is then drawn over the base, an aperture, E, being made in the same for fitting over the frame F. The edges of the cloth are then drawn tightly under and caught on the pins D, on the under side, thus forming a covered base, with the exception of that portion enclosed by the rack or frame F, which is left open for a purpose hereafter shown.

This base is placed in the boiler, resting on the bottom of the same, the clothes are thrown upon it, and around the frame F, thus forming an aperture or opening up through the clothes, as the water in the openings C, becoming heated, is driven into the opening formed by the frame F, rises up in it, and circulates laterally through the clothes, permeating the whole mass, returning again, enters the openings C, thence into the cavity of the rack F, and through the clothes, thus establishing a complete and continuous circulation throughout the clothes, which by this means are soon washed clean by the action of the boiling suds upon them.

I am aware that pipes or tubes or close conduits have been used, which I do not claim, being different in construction and results from the rack or frame described.

What I claim as my improvement, and desire to secure by Letters Patent, is—

1. The open frame or rack F, in combination with the removable base B and boiler, all constructed and operating substantially as set forth.

2. The apron G and base B, in combination with the rack or frame F, substantially as and for the purpose set forth.
